J. M. PEERSON.
FEED MECHANISM FOR PRESSES.
APPLICATION FILED SEPT. 13, 1919.

Patented Apr. 4, 1922.

UNITED STATES PATENT OFFICE.

JAMES M. PEERSON, OF FLORENCE, ALABAMA.

FEED MECHANISM FOR PRESSES.

1,411,299.

Specification of Letters Patent. Patented Apr. 4, 1922.

Application filed September 13, 1919. Serial No. 323,634.

To all whom it may concern:

Be it known that I, JAMES M. PEERSON, a citizen of the United States of America, residing at Florence, in the county of Lauderdale and State of Alabama, have invented certain new and useful Improvements in Feed Mechanism for Presses, of which the following is a specification.

My invention relates to a novel mechanism for feeding the material to be baled or compressed in cotton trampers or reciprocating plunger presses.

My invention is more particularly concerned with the production of a feeder mechanism especially adapted for use with presses having a continuously reciprocating platen. In such presses, and especially in the case of cotton trampers, it is of material importance that the feeder mechanism be adapted, during the interval that the platen is raised out of the press box, to feed the cotton with a quick and rapid stroke and at the same time to distribute it across the press box.

My invention is characterized by the provision of a gravity operated sweeper, which is raised and thrown rearwardly for a gravitating stroke by the platen as the latter nears the completion of its up stroke, the gravity movement of the feeder taking place during the interval required for the platen to complete its up stroke and to approach the press box on its down stroke.

A further distinct advantage of my invention is that the sweeper is adapted both to hold the cotton in the chute on the down stroke of the platen and to hold the cotton under the follow board until the platen enters the press box, the platen acting as it descends to force the sweeper back into what I term its initial position, and to hold it there while completing its down stroke. My invention also comprises the novel details of construction and arrangements of parts which in their preferred embodiment only are illustrated in the accompanying drawings which form a part of this specification and in which:—

Fig. 1 is a side view of my feeder mechanism as applied to a continuous action trumper.

Fig. 2 is a front view of Fig. 1 and with the follow board and sweeper operating mechanism omitted.

Fig. 3 is a plan view of Fig. 1.

Fig. 4 is a side view of the feed chute showing the sweeper in its raised position

and indicating by dotted lines the position to which it is pitched by the lifting action of the platen.

Similar reference numerals refer to similar parts throughout the drawings.

In the embodiment of my invention illustrated, 1 is a typical cotton press-box with which a platen 2 operated by a plunger 3 cooperates in the manner well understood in this art. The platen is preferably continuously reciprocated by any suitable mechanism 4 such as is formally illustrated in the drawings as it forms no essential part of my present invention. The cotton is fed to the press-box down a chute 5 from the condenser 6.

The feeder mechanism is mounted above the feed chute 5 and comprises a pair of vertically swinging arms 7 pivotally connected at one end to the condenser 6 or any other suitable support and at their free ends being pivotally connected to hanger arms 8, which hang vertically and near their lower ends are cross connected by the bars 9 to 80 which are attached the vertical slats 10 which form a sweeper at the lower ends of the hanger arms 8. At the center of the arms 9, I attach a vertical board 11 having on its outer face a wedge shaped lug 12. On the outer side of each hanger arm 8, I mount a flanged roller 13, which rides on the rails 14 suitably attached by straps 15, to the side walls of the chute. The arms near their free ends pass through slots 16 in vertical 90 stop plates 17 that are attached to a timber 18 or other suitable support (see Fig. 2).

At the center of the platen opposite the board 11, I mount an apron 19, which extends from end to end of the platen and carries on its face toward the chute, a stop block 20 against which a pivoted dog 21 is normally held by a cord or chain 22 passing through the apron and over a guide pulley 23 and carrying the suspended 100 counterweight 24 at its free end. The dog is pivotally mounted at 25 on the platen and at its upper end has a notched detent 26, which faces towards the wedge block 12 on the board 11 and is adapted to operate the sweeper in the manner which will now be described.

In Fig. 1 the platen is shown in that part of its up stroke in which it has just emerged from the press box and it will be observed 110 that the pawl 21 has engaged the wedge 12 on the sweeper. As the platen continues its

up stroke the sweeper is lifted substantially vertically, until the arms 7 engage the top wall of the notches 16, which arrest them, so that the continued upward travel of the 5 pawl will result in throwing the sweeper rearwardly towards the upper portion of the chute 5 during which movement the detent 26 becomes disengaged from the wedge block 12, whereupon, the pawl is 10 snapped back to position against the stop block 20 by the counterweight 24 and the sweeper is caused to swing downwardly by the action of the counterweight 27 carried by the frame 28 that is rigidly connected by 15 braces 29 to the hanger arms 8.

As the sweeper is released by the pawl, the action of the counterweight causes the whole sweeper frame to drop from dotted line position shown in Fig. 4, at the same time, the 20 weight being rigid on the hanger arms 8 will tend to swing them to vertical position. The rollers 13 by engagement with the tracks 14 will support the sweeper so that it will not engage the chute bottom and will reduce 25 its friction to a minimum.

The pawl 21 and the position of the wedge 12, as well as the stop plate 17 may be designed to cause the sweeper to swing back as far as desired in the chute and the quick 30 gravitating feed movement of the gate will shoot the mass of accumulated cotton ahead of it under the platen as the latter begins its descent, causing a substantially uniform distribution across the press box and at the 35 same time assuming position which will hold the cotton under the platen until the latter enters the press box. If the sweeper tends to swing over the press box, the platen will move it back to position to close the lower 40 end of the chute and the pawl will remain in contact with the board 11 throughout its stroke so as to prevent the sweeper swinging outwardly under the weight of the cotton in the chute so as to be engaged by the 45 platen on its up stroke. By this arrangement, the sweeper serves as a gate or apron to hold the cotton in the chute and in feeding the cotton it will be observed that the movement of the sweeper is not calculated 50 to produce any dust nor to break or injure the fibre of the cotton.

When it is desired to operate the platen to finish a bale while holding back the feed of cotton in the chute, I provide stop pins 55 31 in the side walls of the chute, which will engage and hold the sweeper in the dotted position shown in Fig. 4 where it will stand and hold the cotton fed from the condenser until it is desired to again start the feed.

60 While I prefer to have the platen throw the light gravitating feed sweeper into position behind the mass of material to be fed, I, nevertheless, claim as part of my invention the use of a sweeper adapted to slide by 65 gravity only freely down the chute until it

has thrust the material ahead of it into the press box. As the quick gravity responsive feed movement of such a sweeper has many advantages, particularly in connection with continuously driven platens such a feed arrangement is claimed regardless of the mechanism employed to lift and place the gravitating sweeper in position to start its feed stroke.

It will be understood that the details of 75 construction of my invention can be widely varied without departing from my invention as set forth in the following claims.

What I claim is:—

1. In a press of the character described, a 80 reciprocable platen, a feed chute, a press box fed by the feed chute, a hinged vertically movable gravitating sweeper and platen operated means comprising a hinged element and a lug engaged thereby to raise and throw 85 the sweeper rearwardly in the chute.

2. In a press of the character described, a press box, a platen reciprocable thereinto, a feed chute, a sweeper hinged above the feed chute and having a hinged downwardly 90 hanging member adapted to move therewith vertically and rearwardly into the feed chute, and means operable by the platen while the platen is rising above the press box to raise and throw the sweeper member upwardly 95 and rearwardly toward the intake end of the feed chute, said sweeper member being adapted to slide responsive to gravity alone down the feed chute for the purposes described.

3. In a press of the character described, a 100 press box, a reciprocable platen, a feed chute, a sweeper normally forming a gate at the lower end of the feed chute, means responsive to the rising movement of the 105 platen above the press box to lift and move the sweeper toward the intake end of the feed chute, and gravity responsive means to move the sweeper downwardly toward the discharge end of the chute, after disengagement 110 from the platen.

4. In a press of the character described, a press box, a reciprocable platen, a feed chute, a sweeper, vertically movable pivoted arms connected to the sweeper, stops to limit 115 the vertical play of said arms, a hinged connection between the sweeper and the free ends of said arms, counter weight means for the sweeper, and a pivoted element adapted to form an operating connection between the 120 rising platen and the sweeper to lift the latter and throw it rearwardly behind the mass of material collected in the chute.

5. In a press of the character described, a press box, a follower, a feed chute, a sweeper 125 having roller supports adapted to ride down the feed chute, a swinging frame above the sweeper, hinged connections between the sweeper and frame, means to limit the vertical play of said frame, a lug on the sweeper, 130

a hinged counter weighted pawl on the platen adapted to raise the sweeper and throw it behind the accumulated mass of cotton in the chute and gravity means to cause the 5 sweeper to force the material ahead of it into the press box.

6. In a feed mechanism for presses, a press box, a feed chute therefore, a feeding sweeper mounted to slide responsive to gravity alone down the feed chute toward its 10 discharge end to discharge material into said press box, and mechanism to return the sweeper to position behind the material to be fed and there to release it for its gravity 15 stroke.

7. In a cotton trumper, the combination

with a press box, a platen and a driving mechanism for continuously reciprocating the platen, of a feed chute, a sweeping feeder mounted to move by gravity downwardly 20 along the chute, and means movable responsive to the up travel of the platen above the press box to raise and pitch the sweeper into position behind the material in the chute, the sweeper being released from its operating 25 mechanism to make its feeding stroke by gravity, while the platen is near the top of its up stroke.

In testimony whereof, I, JAS. M. PEERSON, affix my signature.

JAMES M. PEERSON.
